UNITED STATES PATENT OFFICE.

ANDREW KULAS, OF MARPLE, NEBRASKA.

GAME.

Application filed March 24, 1922. Serial No. 546,260.

To all whom it may concern:

Be it known that ANDREW KULAS, citizen of Germany, residing at Marple, in the county of Box Butte and State of Nebraska, 5 has invented certain new and useful Improvements in Games, of which the following is a specification, reference being had therein to the accompanying drawings.

The invention relates to games and has 10 for its object to provide a game, which will be both interesting and instructive. Also to provide a game which is of a geographical nature and comprises a colored map of the Atlantic Ocean, showing its eastern and 15 western shores, and adjacent the shores, different ports; small spherically shaped differently colored members, which represent ships, and adapted to be made, by tilting the device, to roll into the different ports.

20 A further object is to convey to the mind of the player that the ships of European nations will eventually come to the ports of America and hence the foreign commerce of America enlarged.

25 A further object is to provide a device of this character, which will attract the young, and by reason of its entertaining qualities and its geographical nature will impart knowledge of that part of the earth's 30 surface shown by the device, and stimulate a desire to know more about the rest of the earth's surface, not shown by the device.

A further object is to provide a device of this nature representing a portion of the 35 earth's surface, the body portion of which is round, the inside of the bottom, showing a map of the Atlantic Ocean, ports of the different countries shown by indentations in the bottom, colored spherical members to 40 represent ships, an outside wall and a glass top to form a complete closure to prevent the escape of the spherical members.

With the above and other objects in view 45 the invention resides in the combination and arrangement of parts as hereinafter set forth, shown in the drawings, described and claimed, it being understood that changes in the precise embodiment of the invention may be made within the scope of what is 50 claimed without departing from the spirit of the invention.

In the drawings:—

Figure 1 is a top plan view of the game.

Figure 2 is a vertical sectional view taken 55 on line 2—2 of Figure 1.

Figure 3 is an enlarged perspective view

of a portion of the body member showing one group of the lugs for securing the glass top in position.

Referring to the drawing, the numeral 1 60 designates a round body member of the game and 2 an upwardly extending annular flange carried thereby. The flange is preferably formed integrally with the body member and stamped from the same piece of material. The map is preferably stamped directly on the member 1, however it is to be understood that the map may be printed on paper and adhesively secured thereto. The map shows the Atlantic 70 Ocean, the west coast 3 of the Atlantic Ocean, each country bordering thereon being shown in different colors, and 4 designates ports of the different countries, which ports are formed by indentations in the bottom 5 of the body member 1. The east coast of the Atlantic is designated by the numeral 6, and the main ports of entry of the different countries of said east coast are represented by indentations 7 in the bottom 75 5 of the body member 1. Loosely confined within the body member are differently colored spherical members 8, which members represent ships, and may, by tilting the device as a whole, be rolled into the different ports 4 and 7. Disposed on the inside of the annular flange 2 at diametrically opposite points are spaced lugs 9, which lugs are formed by cutting and bending a portion 80 of the flange 2 to a horizontal position inwardly. Disposed between each group of spaced lugs 9 is an inwardly extending lug 10, which is preferably formed integral with the flange 2 and in the same horizontal plane as the lug 9 and adapted to engage 85 the upper face of the glass cover 12. The lugs 10 may be bent to a vertical position to allow the glass top 12 to be placed in position on the spaced lugs 9, and then again bent back to horizontal positions over the 90 upper surface of the top 12, thus firmly securing the glass top in position and against displacement.

In operation the spherical members 8 are 100 assembled preferably at the lower side of the device as at 13, and then by tilting the device, the spherical members may be made to roll into the indentations 4 and 7, which represent ports of the different countries as 105 shown by different colors on either the east or west coast, thus causing the spherical members 8, which represent the ships to call 110

at the different ports of the different countries, and eventually to call at the ports of North America. If so desired ships may first be started from the foreign ports represented by the numeral 7 to the American ports represented by the numeral 4.

The invention having been set forth what is claimed as new and useful is:-

A game comprising a circular shaped box 10 formed from one piece of flexible metal, a bottom in said box, a side wall formed integral with the bottom, a round glass top disposed within the box, lugs formed from a portion of said side wall by cutting said 15 side wall and bending the lugs inwardly to

horizontal positions in spaced relation to each other, and spaced from the top of the side wall, said lugs engaging the under surface of the glass top adjacent its edge and adjacent each other, lugs formed from the side wall and disposed above and between the first mentioned lugs and engaging the upper side of the glass top, said last named lugs being adapted to be bent to vertical positions for allowing removal of the glass top 20 and to horizontal positions for holding the glass top securely in place.

In testimony whereof I hereunto affix my signature.

ANDREW KULAS.
